Company, Woonsocket, R.I., a corporation of Rhode
Island

Filed Apr. 13, 1962, Ser. No. 187,403
3 Claims. (Cl. 242—46.21)

The present invention relates to improvements in supports for yarn and like textile materials which are to be wound at high speeds, and, in one particular aspect, to novel and improved stabilized bobbin-spindle assemblies of simple low-cost constructions in which troublesome non-linear vibrations and noise are suppressed with such effectiveness that operating speeds and productivity may be vastly increased.

As is well known in textile machinery art, packages of yarns or other textile threads are commonly collected upon spindle-mounted tubular cores or bobbins for further processing and dispensing, it being important both that such bobbins lend themselves to rotations at high speed and that they be quickly and surely receivable on and removable from their mounting spindles. Over the course of the years, bobbin and spindle assemblies have assumed a variety of structural shapes and have been fabricated of many different kinds of materials, depending upon the intended applications; one preferred construction, to which the present teachings are particularly applicable with distinct advantage, involves a generally tubular bobbin which mates loosely with an associated spindle over substantially its entire length and which is mechanically supported by the spindle only near its upper extremity. In such a construction, the rounded tip of a vertically-oriented spindle is mated with a conically-tapered inner surface of the surrounding tubular bobbin, making essentially a circular line contact with it which is advantageous in that the coupling may be made quickly and easily is then not so tight as to interfere substantially with doffing of the bobbin while at the same time sufficing to transmit torques needed to rotate the bobbin and its textile loading. However, this form of coupling has certain of the aspects of a ball-and-socket connection, in that the bobbin may pivot about the rounded tip of the spindle, and the lower portion of the bobbin tends to wobble erratically, particularly at high speeds. The resulting noise is highly disturbing, and the non-linear vibrations may be of such violence that they can impair the winding operations and can have destructive influences upon the bobbins and their spindle mountings. Such wobble, or non-linear vibration of the bobbin about the spindle, is possible because of the loose fit which the bobbin makes with the spindle, this loose fit being dictated both by the need for clearance which facilitates doffing of the bobbin and by the need for positive clearance which prevents the bobbin from jamming with yarn initially wrapped about the base of the spindle before the bobbin is set in place. In accordance with the present teachings, however, the prior relatively low upper limits of bobbin speed are readily surpassed and troublesome noise and non-linear vibrations are very effectively suppressed by stabilizing provisions of remarkable and surprising simplicity, without recourse to complex and costly accessory dampers of conventional types, and without involving radical redesign of either the spindle or bobbin.

It is one of the objects of the present invention, therefore, to provide novel and improved textile bobbin assemblies in which non-linear vibrations and noise are suppressed and, substantially higher speeds of operation and production are promoted, and in which the customary ease and certainty with which bobbins may be mounted on and removed from spindles are not impaired.

2

A further object is to provide stabilized textile bobbins of low-cost and uncomplicated construction which dampen the troublesome effects of non-linear vibrations induced during winding operations.

By way of a summary account of practice of this invention in one of its aspects, there is added to a common form of tubular impregnated laminated paper bobbin, having a conically-tapered seat insert near its upper end, a tubular stabilizer member in the form of a substantially cylindrical tubular bushing which is affixed concentrically within the tubular bobbin near its lower end but above the level to which the acorn or like portion of a mated spindle can project. The inner diameter of the tubular stabilizer member is precisely machined or otherwise formed with a diameter but a few thousandths of an inch greater than the outer shank diameter of the cooperating cylindrical rounded-tip spindles with which the bobbin is used, the inner diameter of the balance of the bobbin below the level of its upper seat being materially in excess of that of the stabilizer member. Upon occurrence of characteristic wobble, or erratic non-linear vibration, of even relatively low amplitude, inner surfaces of the tubular stabilizer member impact against the outer surfaces of the mated cylindrical spindle thereby rapidly dissipating the energy of such vibration effects even at speeds about double those which are currently a practical maximum.

Although the features of this invention which are considered to be novel are set forth in the appended claims, further details as to preferred practices of the invention, as well as the further objects and advantages thereof, may be most readily comprehended through reference to the following description taken in connection with the accompanying drawings, wherein:

FIGURE 1 is a partly cross-sectioned view of a mated bobbin and spindle assembly, including a stabilizer in accordance with the present teachings;

FIGURE 2 illustrates the angular displacements between a spindle and proximate portions of two bobbins having stabilizers at different distances from the spindle tip; and

FIGURE 3 is a partly cross-sectioned view of a bobbin and spindle assembly in which vibration-suppressing effects are promoted at the base of the bobbin.

The apparatus portrayed in FIGURE 1 includes a spindle structure 4 of a known type wherein an outer cylindrical metal sleeve 5 is rotated about a stationary central support post 6, on upper and lower bearings 7 and 8, the support post in turn being mounted upon the usual associated machine framework. At its lower end, the rotatable spindle sleeve is driven at high speeds by way of the whirl 9, and at its uppermost end is capped by a rounded tip 10 which mates with the conically-tapered seat surfaces 11 of a seat insert 12 which is fixed within the surrounding tubular bobbin 13. The sloping and shaping of the respective spindle tip and bobbin seat surfaces are such that an essentially line-type small-area contact is developed between them, this being a condition which has long been known to be advantageous in that the bobbin tends to seat itself accurately on the spindle and yet does not lock in place so tightly as to impair its doffing. Driving torques can be transmitted from spindle to bobbin very satisfactorily through this line-contact socketing alone, and it is then unnecessary that the bobbin make contact with the spindle elsewhere. The latter fact is important because it is difficult to apply and remove bobbins which have more than one portion dimensioned to contact the spindle firmly, and, moreover, it is costly and troublesome to machine several spaced bobbin surfaces so that they are accurately concentric and have precise dimensions needed for tight fit with a spindle. Accordingly, the bobbin 13 is of a loose-fitting or "floating" type

throughout its length below the upper seat 12, although a tubular reducing section 14 is recessed within its base to prevent very great play and, generally, to adapt bobbins of various large sizes to use with a slender spindle of a standard diameter. The seat insert 12 near the top of the bobbin serves this same purpose, of adapting different sizes of bobbins to use with a standard small-diameter spindle, but it should be understood that in some constructions, such as those of wooden bobbins and certain types of laminated paper bobbins, the interior bobbin surfaces themselves may be directly proportioned in accordance with the spindle dimensions. In many instances the illustrated form of bobbin is much preferred, however, because the impregnated laminated paper barrel 15, having sheet-metal shields 16 and 17 at its ends, is of particularly light weight and is highly durable while lending itself to relatively low-cost fabrication.

When a tubular bobbin is to be applied to a spindle for a winding operation (which, for present purposes, is also meant to include spinning or twisting or the like), the yarn or other filamentary-type material is first conventionally secured to the spindle by the wrapping of a few turns about the spindle or about the so-called "acorn" 18 of a suitable material provided near its base for this purpose. Acorn sleeve section 18 is of relatively short axial length but nevertheless projects inwardly of the base of the bobbin and therefore dictates an adequate full radial clearance, 19, which will enable the base of the bobbin to be slipped on and off without binding. Commonly, the radial clearance 19 is at least between about 5 and 12 thousandths of an inch to insure that such binding will not occur. It has been found that spindle and bobbin assemblies of the foregoing type will permit erratic non-linear movements of the bobbin to develop, these being the result of the ball-and-socket type support and the spindle-bobbin clearances. As rotational speeds are sought to be increased to improve production rates, the wobbling motions become more intense and severe and create intolerable noise and impacting of bobbin and spindle. While the only satisfactory solutions to this critical problem would be thought to lie in the use of auxiliary damping provisions of conventional types, or in the undesirable rigid clamping of the bobbin and spindle, it has instead been overcome in accordance with the present invention by the surprisingly simple practice of introducing a low-cost tubular stabilizer sleeve, such as the stabilizer member 20, between the bobbin and spindle at a position well below the upper socketting and above the position of the acorn, and by providing a very minute (ex. 2-3 thousandths) full radial clearance 21 between the inner surface of the stabilizer member 20 and the concentric outer surface of the spindle 5. Slight angular skewing of the bobbin during the initial attempted build-up of the aforementioned non-linear vibrations causes the inner surfaces of the stabilizer member 20 to contact the proximate spindle surfaces, and the energy of such vibrations is immediately absorbed by the spindle, stabilizer member and bobbin. Preferably, the stabilizer member is also fabricated of a fibrous laminated paper or cardboard material which tends to absorb the impacts without wearing or deforming rapidly. The minute clearance 21 between the stabilizer 20 and spindle 5 is effective to limit impacting of the bobbin with the spindle to the stabilizer surfaces only. Permissible amplitudes of erratic bobbin movement are restricted to very low levels, and the vibrational energy involved is dissipated as a result of the impacting, such that the bobbin's lateral movements are damped and its rotation is stabilized. Noise and violent motion are so effectively suppressed that bobbins of the illustrated type may be spun in production operation at about 23,000 r.p.m., which is about double the prior maximum practical speeds. It should be understood that the tubular suppresser 20, being disposed above the level of the spindle acord, cannot interfere with yarn wrapping and therefore permits the needed large radial clearance 19

to be maintained. Further, the stabilizer clearance 21, though minute, is sufficient to permit the rounded-tip spindle to pass through it readily, both on installation and doffing of the bobbin. Total weight of the bobbin is little affected by the addition of the relatively short-length stabilizer member.

Preferably, the stabilizer inserts are introduced well down toward the base of the bobbin. As is exemplified by the showings in FIGURE 2, wherein elements of function corresponding to those in the other illustrations are identified by the same reference characters having distinguishing single-prime accents, the bobbin tube 51 having stabilizer 20' at a relatively short distance 22 from the fulcrumming position about spindle tip 10' must tilt or skew through a certain angle 24 before the stabilizer 20' will engage the side of spindle 5'. The radial gap 23 is then a maximum on one side of the spindle, the clearance (not shown) on the opposite side being zero (i.e., the stabilizer and spindle have contacted one another). Another bobbin tube, 26', having a stabilizer insert 32' fulcrummed at a greater distance 34, need be skewed by only a relatively smaller angle, 36, for a maximum radial gap 35, equal to gap 23, to be developed. From what has been said, it is obviously desirable that the radial width of annular clearance between the stabilizer tube and spindle to be large enough to permit the bobbin and spindle to be mated and separated easily and yet small enough to inhibit as much as possible the erratic non-linear vibrations; the average radial clearance of but a few (ex. 2-3) thousandths of an inch satisfies these requirements, and, while a fulcrumming distance 22 of about five inches is also entirely satisfactory, even less vibration is permissible with a fulcrumming distance 34 of about 7-8 inches.

Equally minute clearance between the spindle and bobbin very close to the fulcrumming or socketting position fails to produce the same benefit because the bobbin must then wobble so violently as to develop the very conditions sought to be avoided before the spindle and bobbin can be made to impact. The construction appearing in FIGURE 3 includes a socket connection which quite incidentally to its main purposes has such characteristics. There, the bobbin 25 is also formed of a thin light-weight tube or barrel, 26, having metal end caps 27 and 28, and having a seat insert, 29, wherein the upper conically-shaped surface 30 mates with the rounded tip 10 of spindle 5. Below the region of shaped surface 30, the seat insert has a short tubular extension 31 the bore of which may clear the concentric spindle surfaces by as little as two thousandths of an inch, this extension being provided in accordance with known prior practice so that it may engage the spindle whenever the bobbin is loosened from and rises in relation to the tip of the spindle. At the latter times, the resulting frictional forces tend to prevent the bobbin from rising further. However, so long as the bobbin is seated on the spindle tip, which is the usual operating condition, the extension 31 is ineffective to suppress any vibrational tendencies, and these can present the aforementioned obstacles to high-speed operation. Accordingly, the tubular stabilizer member 32 is introduced near the base of the bobbin, just above the level to which the acorn section 18 of the spindle projects. Its annular clearance 33 with the spindle 5 is but about 2-3 thousandths of an inch, radially, and its function is as described earlier herein with reference to the stabilizer member 20. Should the bobbin tend to rise from its upper seat, the stabilizer is also effective to suppress the unwanted non-linear vibrations at these times, as well as when the bobbin is properly seated. In the FIGURE 3 embodiment there need be no reducing insert comparable to the member 14 of the FIGURE 1 construction, this element being unnecessary because the low stabilizer member 32 may then serve this added function. Typical stabilizer members may be about an inch long, in bobbins having a total length of about twelve inches,

and may be secured to the interior of the bobbins by an adhesive.

Although cylindrical spindles have been referred to, there are numerous known constructions in which spindles are of a different shape, such as a truncated conical configuration, and the present teachings are of course applicable to these as well. Likewise, although vibration-suppressed bobbins having pivotal suspensions near their upper ends have been specifically discussed, there are also known forms of bobbins, spools, and the like which are driven nearer their lower ends and which yet have certain freedoms for erratic pivotal motions in the nature of wobble near their upper ends, and it should be apparent that the disclosed stabilizer members may in those instances be advantageously exploited near these upper ends.

While specific practices have been described, and while preferred embodiments constructed of preferred materials have been described, it should be understood that various changes, modifications, additions and substitutions may be effected by those skilled in the art without departure from these teachings, and it is aimed in the appended claims to embrace all such variations as fall within the true spirit and scope of this invention.

What we claim as new and desire to secure by Letters Patent of the United States is:

1. A high-speed vibration-suppressed tubular bobbin structure for mounting in combination with an elongated rotatable upright spindle of predetermined dimensions and substantially inflexible construction and having a rounded tip and an acorn portion at the base about which windings of filamentary materials are started, comprising an elongated thin-walled tubular barrel fitting loosely about the spindle, a tubular seat insert member fixed concentrically within said barrel near the upper end thereof and shaped to mate with the rounded tip of the spindle in a ball-and-socket-type connection, and a generally cylindrical tubular stabilizer insert member of laminated paper tubing concentrically within said thin-walled barrel below and spaced from said seat insert member and above the level of said acorn portion of the spindle, said tubular stabilizer insert member having a dimensioned central opening the surfaces of which form a radial clearance of about 2-3 thousandths of an inch with the spindle, whereby non-linear vibrations of the thin-walled barrel pivotally about said connection are damped by impacting of the stabilizer insert member against the substantially inflexible spindle.

2. A high-speed vibration-suppressed tubular bobbin structure for mounting in combination with an elongated rotatable upright spindle of predetermined dimensions and substantially inflexible construction and having a rounded tip and an acorn portion at the base, comprising an elongated thin tubular bobbin of relatively lightweight con-

struction having an internal seat near the upper end thereof shaped to mate in a ball-and-socket-type connection with the spindle near its tip and having an inner substantially cylindrical surface at a relatively large distance below said seat which is of cross-section greater than the cross-sections of portions of the spindle above it and forming a relatively small clearance of but about 2-3 thousandths of an inch with the mated spindle, said surface terminating above the level to which said acorn portion of the spindle projects into the lower end of the bobbin, and the portions of the thin tubular bobbin below said surface forming a clearance about the acorn portion of the substantially inflexible spindle which is greater than said relatively small clearance, whereby non-linear vibrations of said thin lightweight bobbin pivoting about said connection on the spindle are damped by impacting of said surfaces against the mated substantially inflexible spindle.

3. The combination with an elongated rotatable upright spindle of substantially inflexible construction including a rounded tip, of an elongated thin and lightweight tubular bobbin having an internal seat near the upper end thereof shaped to mate in a ball-and-socket-type connection with said spindle near said tip and having a relatively loose fit with said spindle, below said seat, and a stabilizer member in the form of a substantially cylindrical tubular insert of laminated paper tubing concentrically within said lightweight bobbin below and spaced from said seat, said paper tubing stabilizer insert having a central opening the surfaces of which form a radial clearance of but a few thousandths of an inch with the mated spindle, and means adhesively securing said paper tubing insert to the interior of said bobbin at a position near the base thereof wherein said insert is both spaced inwardly of the lower end of the bobbin by an amount needed for the wrapping of wound material about the base of the spindle when winding is about to be started and is spaced from said seat by at least about five inches, whereby non-linear vibrations of the lightweight bobbin pivotally about said connection on the substantially inflexible spindle at high speeds are suppressed by impacting of the stabilizer member against the spindle.
